(57) **CLAIM**

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

The sole FIGURE shows a display screen or portion thereof with icon showing our new design.

The peripheral dashed broken line illustrates a display screen or portion thereof, and forms no part of the claimed design.

**1 Claim, 1 Drawing Sheet
(1 of 1 Drawing Sheet(s) Filed in Color)**

Related U.S. Application Data

a continuation of application No. 29/725,871, filed on Feb. 27, 2020, now Pat. No. Des. 918,247, which is a continuation of application No. 29/622,292, filed on Oct. 16, 2017, now Pat. No. Des. 879,810, which is a continuation of application No. 29/515,146, filed on Jan. 20, 2015, now Pat. No. Des. 803,880.
